UNITED STATES PATENT OFFICE.

CRAWFORD D. LOGAN, OF COALHILL, ARKANSAS, ASSIGNOR OF TWO-THIRDS TO ALBERT V. CHENY AND THOMAS J. GIPSON, OF COALHILL, ARKANSAS.

LOCK.

SPECIFICATION forming part of Letters Patent No. 692,792, dated February 4, 1902.

Application filed September 28, 1901. Serial No. 76,920. (No model.)

To all whom it may concern:

Be it known that I, CRAWFORD D. LOGAN, a citizen of the United States, residing at Coalhill, in the county of Johnson and State of 5 Arkansas, have invented a new and useful Lock, of which the following is a specification.

The present invention relates to permutation-locks, and more particularly to that class 10 set forth in a previous patent granted to me on January 16, 1900, and numbered 641,458. In fact, this invention is designed as an improvement on the construction set forth in said patent, the object being to greatly simplify 15 the structure without sacrificing any of the good features thereof, thereby providing a lock that is made of a minimum number of parts or elements which are of a simple nature and not liable to become deranged. In 20 the former construction a catch was provided, locking means therefor, actuating mechanism for the locking means, and a cover for the actuating mechanism. An operating device was employed for the latch and a separate locking device for the cover.

One of the features of the present invention is to so reconstruct the mechanism that but one device is employed having both functions. Outside of simplifying the structure 25 30 other advantages result from the arrangement which will more readily appear when the construction is understood.

A further feature resides in simpler and more easily understood locking means.

In the accompanying drawings there is fully 35 illustrated the preferred embodiment of the improved lock, and the construction and operation of the same are described in the following specification. It will of course be 40 understood that such modifications may be made from the structure set forth as the claims hereto appended will permit.

In the drawings, Figure 1 is a front view 45 of the lock when in closed position. Fig. 2 is a similar view with the cover thrown back and exposing the actuating mechanism. Fig. 3 is a vertical sectional view taken on the line X X of Fig. 1. Fig. 4 is a detail perspective view of one of the tumblers and the 50 actuating means therefor. Fig. 5 is a detail

perspective view of the other tumbler; and Fig. 6 is a perspective view of the holding-disk for the tumbler illustrated in Fig. 5.

Similar numerals of reference designate corresponding parts in all the figures of the drawings.

The lock shown in the accompanying drawings is applied to a hasp intended for locking trunks, chests, or any analogous receptacle usually employing a hasp. In order to show 60 the application of the invention, therefore, a portion of such a receptacle is shown, the body-wall being designated 10 and the coacting cover-wall 11. The hasp is designated as a whole by the reference-numeral 12 and 65 comprises a pair of hinged leaves, one of which, as 13, is secured to the wall 11, while the other, 14, carries the locking mechanism. In the construction shown this mechanism is as follows: A sliding catch-bolt 15 is located 70 upon the under face of the leaf 14, having at one end a retaining-finger 16 and at the other end an arm 17, that is adapted to fit in recesses or notches 18 of rotary tumblers 19 and 20, located upon the under face of the leaf 75 14 when said notches are alined.

The tumblers are mounted and operated in the following manner: A sleeve 21 is rotatably mounted in an opening 22 in the leaf 14, said sleeve carrying on its outer end a collar 80 23, having a suitable indicating-scale 24, which is arranged to register with a scale 25 upon the outer face of the leaf. The sleeve is provided on its inner end with a tooth 26, that is arranged to engage in one of a series 85 of notches 27, arranged in the edge of a central opening 28 in the tumbler 19, which opening receives the inner end of the sleeve.

Passing through the sleeve and rotatably mounted therein is a post 29, the outer end 90 of which has a milled operating-head 30 and an annular flange 31, fitting in a seat 32 in the outer face of the collar 23. This flange is provided with an indicating-scale, as 34, which coacts with the scale 24 of the collar. 95 The opposite end of the post is angular in cross-section, and the tumbler 20 is rotatably mounted upon the inner end contiguous to this angular portion. A holding-disk 35 is detachably fitted upon the angular portion of 100

the post and is provided on its inner face with a pin 36, arranged to detachably engage in one of an annular series of openings 37 in the tumbler 20. A washer 38 is secured to the 5 post over the holding-disk by means of a screw 39, that is threaded into the end of the post. By this means it will be seen that the several tumblers are held on their respective operating devices by means of a single washer and 10 screw 38 and 39, but that each tumbler is capable of independent movement, and the combination may be changed by changing the relation of the notches 18 and the indicating-scales. A cylindrical boxing 40 normally in- 15 closes the tumblers and is held in place by fastening-screws, as 41.

The operation of the lock will be clear to those skilled in the art. Having first located the notches of the tumblers so that they will 20 be in alinement when the scales are in a certain predetermined relation and said notches being also in alinement with the end of the arm 17 of the catch-bolt, it will be seen that said catch-bolt may be slid inwardly, and, vice 25 versa, when the bolt is slid outwardly and the tumblers rotated until their respective notches are out of alinement the bolt will be locked against such inward movement. The locking-finger 16 of the bolt is arranged when 30 in its projected position to engage the holding-ledge 42 of a metallic casing 43, that is secured in a suitable opening made for the purpose in the body-wall 10, said casing being arranged to receive the tumbler mechanism and the catch-bolt. In order to protect the 35 actuating mechanism of the locking means, a cover or cap-plate 44 is hinged, as at 45, to the swinging leaf 14 and is provided with a pocket 46, that receives the projecting portions of 40 said actuating mechanism. This cover is furthermore provided at its free end with a key-hole-opening 47.

The operating device for the catch-bolt 15 is in the form of a stem 48, rotatably secured 45 to said bolt and extending through a slot 49 in the leaf 14, which slot permits of the necessary sliding movement of the pin. The projecting end of the pin is provided with an enlarged circular head 50, having an offset 50 locking-lug 51 at its upper edge. This head is arranged to fit in the opening 47 of the swinging leaf, but with the lug 51 located above the same, so that by turning said head the lug will be out of alinement with the 55 notch of the keyhole-opening, and thus hold the cap-plate in operative position over the actuating mechanism.

The operation of the device will be readily apparent. To unlock the hasp, the cap-plate 60 is first thrown back to the position shown in Fig. 2 and the tumblers actuated in the manner above pointed out until the bolt is released. When this is accomplished, said bolt is thrown to its inner position, so that its 65 locking-finger will disengage the holding-ledge and the hasp may be raised. To relock

the device, the operation is reversed, after which the cap-plate is swung down over the actuating mechanism and the head rotated until the lug is out of alinement with the slot 70 of the keyhole. By this construction it will be seen that the operating mechanism is greatly simplified, thus employing a fewer number of elements than in the former construction and affording a more compact 75 structure. Further than this, however, the means for operating the bolt and locking the cover in place besides being much simpler is more readily understood. Furthermore, when the cap-plate is locked in place the circular 80 head fitting snugly in the opening thereof will serve as an additional means for holding the bolt in projected position, and thus relieve the tumblers of a portion of any backward strain upon the bolt. 85

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages 90 of the invention. 95

Having thus described my invention, what I claim as new, and desire to secure by Letters Patent, is—

1. The combination with a hasp, of a catch for holding the hasp, locking means for the 100 catch, actuating mechanism for the locking means, a cover removably fitting over the actuating mechanism, and an operating device for the catch, said device also constituting holding means that engage the cover to secure said cover over the actuating mechanism. 105

2. The combination with a hasp, of a holding-catch carried by the hasp, locking means for the catch also carried by the hasp, actuating mechanism for the locking means located upon the exposed face of the hasp, a cover for the actuating mechanism hinged to the hasp and arranged to removably fit over said actuating mechanism, and an operating device for the catch, said device also constituting holding means that engage the cover to secure said cover over the actuating mechanism. 115

3. The combination with a hasp, of a sliding catch-bolt carried by the hasp, locking 120 means for the bolt also carried by the hasp, actuating mechanism for the locking means located upon the exposed face of the hasp, a cover for the actuating mechanism hinged to the hasp, an operating-stem secured to the 125 catch-bolt and projecting above the face of the hasp, and a rotatable head secured to the projecting portion of the stem and arranged to engage the cover to hold the same in operative position over the lock-actuating mechanism. 130

4. The combination with a hasp, of a slid-

ing catch-bolt arranged upon the under side of the hasp, locking means for the bolt also carried by the hasp, actuating mechanism for the locking means located upon the exposed face of the hasp, a cover for the actuating mechanism hinged to the hasp and provided in its free end with an opening, an operating-stem rotatably secured to the catch-bolt, said stem extending through and projecting above the face of the hasp, and a head secured to the projecting portion of the stem and arranged to engage in the opening of the cover, said head being provided with an offset lug that engages said cover to hold the same in operative position over the lock-actuating mechanism.

5. In a lock, the combination with a plate, of a catch movably connected thereto, locking mechanism for the catch, said mechanism comprising a sleeve rotatably mounted in the plate and having an operating-collar arranged upon one side thereof, a tumbler detachably fitted upon the sleeve on the opposite side of the plate, a post rotatably mounted in the sleeve and having an operating-head at one end, a tumbler rotatably mounted upon the other end, a holding device fitted upon the post and detachably securing the tumbler and

post against relative movement, and a fastener for holding said securing device in place. 30

6. In a lock, the combination with a plate, of a sliding bolt arranged upon the under side of the plate, and locking mechanism for the bolt, said mechanism comprising a sleeve rotatably mounted on the plate and having an operating-collar located upon the outer side thereof, a tumbler detachably fitted upon the sleeve on the inner side of the plate, a post rotatably mounted in the sleeve and having an operating-head arranged upon the outer 35 side of the plate, the other end of said base being angular in cross-section, a tumbler rotatably mounted upon the post contiguous to the angular portion, a holding-disk fitted upon the angular portion and engaging the 40 rotatable tumbler to hold the post and tumbler against relative movement, a washer located over the disk, and a screw passing through the washer and engaging the post.

In testimony that I claim the foregoing as 50 my own I have hereto affixed my signature in the presence of two witnesses.
